UNITED STATES PATENT OFFICE.

FRANK CARTLIDGE, OF CLAREMONT, NEW HAMPSHIRE, ASSIGNOR TO SULLIVAN MACHINERY COMPANY, A CORPORATION OF MASSACHUSETTS.

MINING MACHINE.

Application filed June 10, 1918, Serial No. 239,269. Renewed September 16, 1925.

This invention relates to mining machines, and more particularly, although not exclusively, to shearing machines, i. e., to machines for cutting vertical kerfs in a mine wall or 5 face.

The invention has for an object to provide an improved truck mounted machine of this character. A further object of the invention is to provide an improved machine adapted 10 to operate upon a mine face extending transverse to the trackway upon which the machine travels, as in entry driving, or upon a face extending substantially parallel to said trackway, and at either side thereof, as in 15 opening room necks; said machine being capable of producing a cut in any desired vertical plane, and comprising improved means for guiding the cutting mechanism into close proximity to the face to be cut, irrespective of the distance (within limits) of 20 said face from the trackway, together with improved means for securely supporting the parts during the cutting operation.

The foregoing and other objects of the invention, together with means whereby the same may be carried into effect, will best be understood from the following description of one form or embodiment thereof illustrated in the accompanying drawings.

30 In said drawings,—

Fig. 1 is a side elevation, and Fig. 2 a plan view, of the complete machine.

Fig. 3 is an enlarged plan view, partly broken away, of the cutting mechanism.

35 Figs. 4 and 5 are detail sections on the lines 4—4 and 5—5, respectively, Fig. 3.

Fig. 6 is an elevation on a reduced scale, illustrating the operation of the machine in entry driving.

40 Fig. 7 is a plan view on a reduced scale, illustrating the position of the machine when operating upon a face parallel to the trackway, as in opening a room neck.

Fig. 8 is a view similar to Fig. 7, showing 45 the parts adjusted to cause the cutting mechanism to cut at the opposite side of the machine.

The truck upon which the machine is transported comprises a pair of parallel ways 50 10 connected at their rear ends by a transverse brace 18 and mounted on wheels 11 adapted to run upon the usual trackway 12. As herein shown, said truck is of the self-propelled type, being driven by an electric 55 or other motor 13 provided with a suitable

controller 14 and connected by a sprocket chain 15 with the axle of the rear wheels 11.

Guided for movement longitudinally of the truck in the ways 10 is a slide 16, said slide being movable in said ways by means of 60 a screw 17 in threaded engagement with said slide and journaled in the brace 18. Pivoted at one end at 19 to the slide 16, for movement transversely of the machine in a horizontal plane, is a supporting arm 20. Upon 65 the opposite end of the arm 20 is mounted, for angular movement about a pivot 21, a guide or frame 22 provided with a pair of parallel, horizontally disposed ways 23 in which the cutting mechanism is mounted for 70 movement longitudinally of said guide.

The cutting mechanism comprises a complete mining machine including a casing 24 containing the operating mechanism, and a cutter bar 25 carrying the usual cutter chain 75 26 provided with cutter bits 27. Said cutter bar is mounted, as hereinafter more fully described, to swing about the axis of a transverse horizontal shaft 28 having its ends fixed in the casing 24, and when so swung said cutter bar moves in a substantially vertical plane between the ways 23. The operating mechanism within the casing 24 comprises an electric or other motor 29 having a suitable controller 29a and a shaft 30 operatively connected with mechanism for moving the cutting mechanism in the ways 23, mechanism for actuating the cutter chain 26 on the bar 25, and mechanism for swinging the cutter bar 25 about the shaft 28. 80 85 90

For feeding or moving the cutting mechanism in the ways 23, there is provided a chain or other flexible feeding element 31 which, when in operation, is connected at one end to a suitable fixture 32 at the forward end of one of the ways 23, passes about a feed sprocket 33 and guide sprockets 34 on the casing 24, and is connected at its opposite end to a suitable fixture 35 at the rear end of the guide 22. By rotating the feed sprocket 33 in one direction or the other, the cutting mechanism is moved longitudinally in the ways 23, either forwardly or backwardly. For so rotating the feed sprocket 33, the following mechanism is provided. Fixed to the motor shaft 30 is a pinion 36 which meshes with a gear 37 fast on a shaft 38 suitably journaled in the casing 24 and carrying a worm 39 which meshes with a worm gear 40 fast on an upright shaft 41 100 105 110

journaled in the casing 24 and in a horizontal web 42 therein. The feed sprocket 33 is loosely mounted on the shaft 41 and has secured thereto or formed integral therewith 5 an internal gear 41^a which meshes with a pinion 41^b fast on an upright shaft 41^c journaled in a bracket 41^d in the casing 24. The shaft 41^c has fast thereon a gear 41^e which meshes with a gear 41^f loose on the 10 shaft 41. A double acting clutch 43 operated by a controlling handle 44 is adapted to connect either the sprocket 33 or the gear 41^e to the shaft 41 for rotation therewith, thereby causing rotation of said feed 15 sprocket in either direction. When the clutch 43 is in the neutral position shown in Fig. 4 the feed sprocket is idle.

The cutter chain 26 is actuated by a sprocket 45 having a hub 46 rotatably 20 mounted on the shaft 28. Keyed to the hub 46 is a bevel gear 47 which meshes with a bevel pinion 48 fast on a shaft 49 suitably journaled in the casing 24. Keyed or otherwise secured to the shaft 49 is a gear 50 25 which meshes with a pinion 51 on the front end of the motor shaft 30.

The cutter bar 25 is carried by an arm 52 projecting from a hub 53 rotatably mounted on the shaft 28. As shown in Figs. 30 2 and 3, the cutter bar 25 is laterally offset with respect to the arm 52 to bring said cutter bar into alinement with the sprocket 45. Keyed to the hub 53 is a worm gear 54 which meshes with a worm 55 on a longitudinal 35 shaft 56 suitably journaled in the casing 24. Loosely mounted on the shaft 56 is a pair of bevel gears 57 controlled by a clutch 58 operated by a handle 59, whereby said gears 57 may be alternatively clutched to the shaft 40 56 or both may be disconnected therefrom. Meshing with the gears 57 is a bevel gear 60 rotatably mounted on a stud shaft 61 carried by the casing 24. Secured to or formed integral with the gear 60 is a gear 62 which 45 meshes with a pinion 63 fast on the shaft 41. By the foregoing connections it will be seen that either of the gears 57 may be clutched to the shaft 56 to cause the cutter bar to be swung either upwardly or downwardly about the axis of the shaft 28, or that, by disconnecting both of said gears from said shaft, the cutter bar may be held stationary by engagement of the worm 55 with the worm gear 54. It will be noted 55 that this mechanism for adjusting the position of the cutter bar in a vertical plane, this bar swinging mechanism, is, so to speak, a distinct mechanism, though driven from the feed operating mechanism, and that it is 60 a marked improvement over forms of bar swinging mechanism in which a single strand of chain or rope is connected in different ways to swing a bar in opposite directions, this mechanism including what may be called, for purposes of clarity and

comparison, permanent connections with the bar which are capable of transmitting without any readjustment thereof a bar swinging force in either direction, whereby there are eliminated the loss of time and the 70 labor incident to rereeing etc., in the chain form of bar swinging mechanism referred to.

The pivotal mounting of the guide 22 upon the supporting arm 20 and the pivotal 75 mounting of the latter upon the truck provide for a substantially universal adjustability of said guide and the cutting mechanism carried thereby. For example, the guide 22 may be adjusted angularly with respect to the truck about the pivot 21, in order to position the same transversely of the truck with the forward ends of the guides 23 extending in either direction from said truck and trackway. The arm 20 may 80 also be swung about the pivot 19 to move the guide 22 transversely of the truck and trackway and longitudinally of itself to position the forward ends of the ways 23 at any desired distance at one side or the other of the trackway, thereby bringing the ends of said ways into any desired proximity to a wall or face extending parallel to said trackway at either side thereof irrespective of the distance of said wall or face 85 from said trackway. Furthermore, longitudinal movement of the slide 16 by means of the screw 17 permits the position of said guide longitudinally of said truck to remain constant irrespective of its other adjustments.

Means are provided for supporting the projecting ends of the guide 22 and arm 20 when said guide is positioned transversely of the truck, as shown in Figs. 7 and 8. For 105 supporting the forward ends of the ways 23, each of said ways has pivoted thereto, at its outer side, a jack 64 adapted to be swung from its normal horizontal position shown in Fig. 1 into an upright position, as shown in Fig. 6 and, when in the latter position, to engage at its opposite ends the roof and bottom of the mine, respectively, thereby securely holding the ends of the guides 23 110 against movement in any direction. For supporting the outer end of the arm 20 and the rear end of the guide 22, there is provided a pair of laterally movable folding brackets 65 pivoted at 66 to the ways 10 at opposite sides of the truck. Said brackets 65 normally occupy a position parallel to the truck, as shown in Figs. 1 and 2, but when the guide 22 is swung into a position transverse to the truck one or the other of the brackets 65, depending upon the direction in which said guide is turned, may be swung laterally outward about its pivot into the position shown in Figs. 7 and 8 beneath the outer end of the arm 20. Pivoted to the outer end of each of the brackets 65 is a 120 125 130

vertically swinging folding upright 67 having an adjustable foot 68. The uprights 67 normally occupy the positions shown in Figs. 1 and 2, and may be retained in said position by suitable supporting brackets 69 carried by the ways 10. When one or the other of the brackets 65 is swung outwardly into its supporting position, the corresponding upright 67 is turned downwardly and its foot 68 adjusted to engage the mine bottom, there-by supporting the outer end of said bracket. 70

For transportation about the mine, the guide 22 and arm 20 are turned into a position parallel to the length of the truck, as shown in Figs. 1, 2, and 6, this being also the position of the parts in the operation of entry driving or in cutting a face transverse to the length of the trackway 12. The latter operation is illustrated in Fig. 6 and is as follows: The truck is moved on the trackway 12 into a position to bring the ends of the ways 23 as closely as possible or convenient to the face to be cut, and the jacks 64 turned into their upright positions to support said ways in this position. The motor having been started, the clutch 58 is operated to cause the cutter bar 25 to be swung upwardly into the position shown in full lines in Fig. 6, and is thereafter released to cause said cutter bar to be held in this position. The clutch 48 is then operated to connect the feed sprocket 38 with the shaft 42 in a manner to cause the cutting mechanism to be fed forwardly in the ways 23 from the position shown in full lines in Fig. 6 into the dotted line position indicated by the letter A in said figure, thereby causing the cutter bar to enter the face. The clutch 58 is then again operated in a manner to cause the cutter bar to be swung downwardly from the dotted line position A into the dotted line position B, making a vertical cut, said clutch being then disconnected to cause said cutter bar to be retained in this position. Finally, the feed sprocket 38 is again actuated to cause the cutting mechanism to move rearwardly from the dotted line position B into the dotted line position C, thereby completing the cut. 100

For the purpose of making a cut in a face parallel to the trackway 12, the arm 20 and guide 22 are swung into the position shown in Fig. 7, or into that shown in Fig. 8, depending upon the side of the trackway at which said face is located. In so positioning the parts the ends of the ways 23 are placed as closely as possible or convenient to the face to be cut, the pivots 19 and 21 permitting such positioning of the parts. The proper bracket 65 is then swung laterally and set on its upright 67 to support the rear end of the guide 22, the jacks 64 are turned into their operative position, as above explained, and the cutting mechanism operated in the manner above described in order to produce the cut. While the guide 22 is shown in Figs. 7 and 8 as occupying positions substantially at right angles to the truck and trackway, it will be seen that said guide may be swung into substantially any angular position with respect to said truck and trackway to cause the cutter bar 25 to be swung in substantially any vertical plane, depending upon the nature and position of the cut desired. 105

It will be seen that by virtue of the arrangement above described, whereby the cutter bar is permitted to move in a vertical plane between the ways 23, and whereby said ways may be positioned as closely as desirable to the face to be cut, the cutting mechanism may be supported and guided in close proximity to said face while permitting a movement of the parts into the dotted line position C shown in Fig. 6, as is necessary in order to complete a relatively deep cut with a long cutter bar. 110

While I have in this application specifically described one form which my invention may assume in practice, it will be understood that this form of the same is shown for purposes of illustration and that the invention may be modified and embodied in other forms without departing from its spirit or the scope of the appended claims. 115

What I claim as new and desire to secure by Letters Patent is:

1. In a mining machine, the combination with a truck, of a guide normally disposed longitudinally thereof, kerf cutting mechanism including a pivoted cutter bar disposable longitudinally of said guide and having its pivot disposable in a vertical plane intersecting said guide transversely between its ends and movable in said guide longitudinally of the latter, and means for mounting said guide on said truck permitting angular and longitudinal movement of said guide relative to said truck. 120

2. In a mining machine, the combination with a truck, of a guide normally disposed longitudinally thereof, cutting mechanism including a pivoted cutter bar disposable longitudinally of said guide and having its pivot disposable in a transverse plane intersecting said guide between its ends and movable in said guide longitudinally of the latter during the cutting operation, and means for mounting said guide on said truck permitting angular and longitudinal movement of said guide. 125

3. In a mining machine, the combination with a truck, of an open-ended guide normally disposed longitudinally thereof, cutting mechanism including a pivoted cutter bar disposable longitudinally of said guide and having its pivot disposable in a transverse plane intersecting said guide between its ends and movable in said guide longitudinally of the latter, and means for mounting

said guide on said truck permitting angular and longitudinal movement of said guide.

4. In a mining machine, the combination with a truck, of a guide, kerf cutting mechanism including a motor and movable bodily under its own power in said guide longitudinally of the latter, and means for mounting said guide on said truck permitting angular and longitudinal movement of said

10 guide relative to said truck in a single horizontal plane.

5. In a mining machine, the combination with a truck adapted to run upon a trackway, of a guide movable longitudinally thereof, cutting mechanism disposed longitudinally of said guide and movable in said guide longitudinally of the latter said cutting mechanism having a cutter bar and means for cutting material along one side

15 thereof throughout its length, and means for mounting said guide on said truck permitting movement of said guide transversely of said trackway while said guide occupies a position at right angles to the direction of

20 said trackway.

6. In a mining machine, the combination with a truck adapted to run upon a trackway, of a guide normally disposed longitudinally thereof, cutting mechanism disposed longitudinally of said guide and movable in said guide longitudinally of the latter, and means for mounting said guide on said truck permitting angular movement of said guide and bodily movement of said

25 guide transversely of said trackway while said guide is disposed at right angles to said trackway.

7. In a mining machine, the combination with a truck adapted to run upon a trackway, of a guide normally disposed longitudinally thereof, and kerf cutting mechanism disposed longitudinally of said guide and movable in said guide longitudinally of the latter, said machine having provision for

40 angularly and bodily positioning said guide with respect to said truck to bring its end at one side of said trackway and beyond the latter and varying the distance of said end from said trackway irrespective of the angular position of said guide.

8. In a mining machine, the combination with a truck, of a guide normally disposed longitudinally thereof, and kerf cutting mechanism disposable longitudinally of said

45 guide and movable in said guide longitudinally of the latter, said guide being movable into a position transverse to said truck and being longitudinally movable relative to said truck when in a position extending longitudinally of said truck.

9. In a mining machine, the combination with a truck, of a supporting arm pivoted at one end to said truck for movement transversely thereof whereby the opposite end

50 thereof is disposed outside the lateral edge

of the truck, kerf cutting mechanism movably carried on said opposite end of said arm and including a pivoted cutter bar, and means driven by said kerf cutting mechanism for moving the latter relative to said arm to effect a movement of translation of said mechanism.

10. In a mining machine, the combination with a truck, of a supporting arm pivoted at one end to said truck for movement transversely thereof whereby the opposite end thereof is disposed outside the lateral edge of the truck, angularly adjustable kerf cutting mechanism carried by said opposite end of said arm and including a pivoted cutter bar and means driven by said kerf cutting mechanism for feeding the latter transversely of said arm and bodily relative thereto.

11. In a mining machine, the combination with a truck, of a supporting arm pivoted at one end to said truck for movement transversely thereof, a guide carried by the opposite end of said arm, and cutting mechanism movable in said guide and disposed longitudinally of the latter and including a pivoted cutter bar.

12. In a mining machine, the combination with a truck, of a supporting arm pivoted at one end to said truck for movement transversely thereof, a guide pivotally mounted on the opposite end of said arm, and cutting mechanism movable in said guide and disposed longitudinally of the latter and including a pivoted cutter bar.

13. In a mining apparatus, a support, a pivot thereon movable bodily transversely relative thereto in a single horizontal plane, guiding means movable transversely about said pivot, and kerf cutting mechanism movable in said guiding means and normally disposed longitudinally thereof.

14. In a mining machine, the combination with a truck, of a guide normally disposed longitudinally thereof, and mechanism for cutting a vertical kerf, said mechanism including a pivoted cutter bar disposable longitudinally of said guide and having its pivot disposable in a vertical plane intersecting said guide transversely between its ends and being movable in said guide longitudinally of the latter, and said guide being angularly and longitudinally movable relative to said truck.

15. In a mining machine, the combination with a truck, of a guide normally disposed longitudinally thereof, and cutting mechanism disposable longitudinally of said guide and movable in said guide longitudinally of the latter, said cutting mechanism including a vertically swinging cutter bar having its pivot disposed in a transverse vertical plane intersecting said guide between its ends, and said guide being angularly and longitudinally movable relative to said truck.

16. In a mining machine, the combination with a truck, of a pair of horizontally disposed parallel ways, and cutting mechanism movable in said ways longitudinally of the latter, said cutting mechanism including a vertically swinging cutter bar movable between said ways, and said ways being angularly and longitudinally movable on said truck. 5
17. In a mining machine, the combination with a truck, of a guide angularly and longitudinally movable on said truck, cutting mechanism in said guide including a cutter bar, a motor, and a feed sprocket actuated by said motor, and a feed chain connected at its ends to said guide, said feed chain cooperating with said feed sprocket to move said cutting mechanism longitudinally in said guide. 10
18. In a mining machine, the combination with a truck, of a guide normally disposed and movable longitudinally of said truck, cutting mechanism movable in said guide and normally disposed longitudinally of the latter, said guide being movable into a position transverse to said truck, and jacks carried by said guide for supporting the same when in transverse position. 15
19. In a mining machine, the combination with a truck, of a guide normally disposed longitudinally of said truck, cutting mechanism movable in said guide longitudinally of the latter, said guide being movable into a position transverse to said truck, and a folding bracket on said truck for supporting said guide when in transverse position. 20
20. In a mining machine, the combination with a truck, of a guide on said truck, cutting mechanism movable in said guide longitudinally of the latter said guide being movable into a position transverse to said truck, folding brackets on said truck for supporting said guide when in transverse position, and folding uprights carried by said brackets for supporting the same. 25
21. In a mining machine, in combination, a truck, a guide on said truck, cutting mechanism movable in said guide longitudinally of the latter, said guide being movable into a position transverse to said truck, a pair of folding jacks carried by one end of said guide for supporting the same when in transverse position, a folding bracket on said truck for supporting the opposite end of said guide, and a folding upright carried by said bracket for supporting the same. 30
22. In a mining machine, in combination, a truck, a supporting arm pivoted at one end to said truck for movement transversely thereof, a guide pivoted on the opposite end of said arm, cutting mechanism movable in said guide longitudinally of the latter, and folding brackets on said truck for supporting said arm and guide. 35
23. In a mining machine, in combination, a truck, a supporting arm pivoted at one end to said truck for movement transversely thereof, said arm and its pivot being also movable longitudinally of said truck, and kerf cutting mechanism movably mounted on the opposite end of said arm and including a guide pivoted on the latter and cutting mechanism movable relative to said guide. 40
24. In a mining machine, in combination, a truck, a guide extending longitudinally of said truck, a slide movable in said guide, a screw for moving said slide in said guide, a supporting arm normally disposed longitudinally of said truck and pivoted at one end to said slide for movement in a plane transversely of said truck, and kerf cutting mechanism movably mounted on the opposite end of said arm. 45
25. In a mining machine, in combination, a truck, a guide extending longitudinally of said truck, a slide movable in said guide, a screw for moving said slide in said guide, a supporting arm pivoted at one end to said slide for movement transversely of said truck, a guide pivotally mounted on the opposite end of said arm, and cutting mechanism movable in said guide longitudinally of the latter. 50
26. In a mining machine, a swinging cutter bar cutting throughout its length, a worm gear rigidly connected to said bar, a worm cooperating with said gear for swinging said bar in a plane and for holding the same in adjusted position, a truck, and means including a motor reciprocable with and actuating said bar and operable to rotate said worm for reciprocating said swinging mechanism and said bar relative to said truck when the bar is disposed in opposite angular positions relative to its path of reciprocation. 55
27. In a mining machine, in combination, a truck adapted to run upon a trackway, a normally longitudinally extending guide on said truck disposed transversely thereof, and cutting mechanism disposed longitudinally of said guide and movable in said guide longitudinally of the latter during the cutting operation, said guide being adjustable longitudinally of said truck and also transversely with respect thereto while maintaining a constant angle therewith to vary the distance of its end from the trackway. 60
28. In a device for cutting a kerf in an entry, a support adapted to be placed in the entry, a normally longitudinally extending guide mounted thereon and movable longitudinally and angularly relative thereto and having a length substantially equal to the width of the entry, and cutting mechanism mounted on said guide of less length than the latter. 65
29. In a mining machine, a machine frame including a motor, cutting mechanism at one end of said motor including a swinging cut- 70 75 80 85 90 95 100 105 110 115 120 125 130

- ter bar disposed in a vertical plane, and means for operating said cutting mechanism and swinging said bar respectively connected to opposite ends of said motor, said means for swinging said bar including a power transmitting element rigid with the bar, a rotatable power transmitting element having a power connection with said motor, and permanent power transmitting connections between said member and element operative to transmit bar swinging force to said bar in either direction.
30. In a mining machine, a machine frame including a motor, cutting and feeding mechanisms connected to opposite ends thereof, said cutting mechanism being adjustable and disposed in a vertical plane, and means for adjusting said cutting mechanism comprising distinct power transmitting connections operative to transmit a bar swinging torque in opposite directions and having an initial driving gear driven by said feeding mechanism.
31. In a mining machine, a machine frame including a motor, cutting and feeding mechanisms connected to opposite ends thereof, said cutting mechanism being adjustable and disposed in a vertical plane, and means for adjusting said cutting mechanism connectible at will with said feeding mechanism, said means for adjusting said cutting mechanism having permanent connections with the latter operative to transmit positively thereto adjusting movement in opposite directions.
32. In a mining machine, a machine frame including a motor, cutting and feeding mechanisms at opposite ends thereof, cutter adjusting mechanism for adjusting said cutting mechanism in a vertical plane, and having permanent connection with said cutting mechanism operative to transmit positively thereto adjusting movement in opposite directions, and means for actuating one of said mechanisms from the front end of the motor and the remainder from the rear end of the motor.
33. In a mining machine, a machine frame movable rectilinearly during cutting and including a motor having an axis of rotation parallel to the direction of rectilinear movement, cutting mechanism including a cutter bar adjustable on an axis on the front end of said frame, means for driving said cutting mechanism from one end of said motor, and means for adjusting the bar about its axis driven from the opposite end of said motor, said means for adjusting said bar including a power transmitting element rigid with the bar, a rotatable power transmitting element having a power connection with the motor, and permanent power transmitting connections between said member and element operative to transmit bar adjusting force to said bar in either direction.
34. In a mining machine, a machine frame including a motor, cutting mechanism including a cutter bar adjustable on a substantially horizontal transverse axis on the front end of said frame, means for driving said cutting mechanism from one end of said motor, and means for adjusting the bar about its axis driven from the opposite end of said motor, said means for adjusting said bar including a power transmitting element rigid with the bar, a rotatable power transmitting element having a power connection with the motor, and permanent power transmitting connections between said member and element operative to transmit bar adjusting force to said bar in either direction.
35. In a mining machine, a machine frame including a motor, cutting mechanism including a cutter bar adjustable on an axis on the front end of said frame, means for driving said cutting mechanism from one end of said motor, means for adjusting the bar about its axis driven from the opposite end of said motor and comprising permanent connections with said bar operative to transmit positively thereto adjusting movements in opposite directions, and feeding mechanism for said frame operative to feed the same rectilinearly in opposite directions towards and from a face during cutting and driven from the last mentioned end of said motor and driving said adjusting means.
36. In a mining machine, a machine frame including a motor, cutting mechanism including a cutter bar adjustable on a substantially horizontal transverse axis on the front end of said frame, means for driving said cutting mechanism from one end of said motor, means for adjusting the bar about its axis driven from the opposite end of said motor, and comprising permanent connections with said bar operative to transmit positively thereto adjusting movements in opposite directions, and feeding mechanism for said frame driven from the last mentioned end of said motor and driving said adjusting means.
37. In a mining apparatus, a wheeled truck, a support thereon presenting a guideway, kerf cutting mechanism including a pivoted cutter bar movable longitudinally of said guideway with its pivot disposed between the sides of the latter whereby said bar is swingable through between the sides of the guideway, and feeding mechanism for feeding said cutting mechanism relative to said guideway including feed operating means movable with said cutting mechanism and cooperating flexible feeding means.
38. In a mining apparatus, a wheeled truck, a support thereon presenting a guideway, kerf cutting mechanism including a pivoted cutter bar movable longitudinally of said guideway, and feeding mechanism for feeding said cutting mechanism relative

to said guideway including feed operating means movable with said cutting mechanism and cooperating flexible feeding means having its free ends connectible to the frame at longitudinally spaced points relative to both of which said feed operating means moves bodily during feeding.

39. In a mining apparatus, a wheeled truck, a support presenting a plurality of spaced guideways, kerf cutting mechanism including a pivoted cutter bar movable longitudinally of said guideways and swinging between the same, and feeding means for feeding said mechanism relative to said guideway including feed operating means movable with said mechanism and cooperating flexible feeding means.

40. In a mining apparatus, a wheeled truck, a support presenting a plurality of horizontal laterally spaced guideways, kerf cutting mechanism including a pivoted cutter bar movable longitudinally of said guideways and swinging between the same in a vertical plane, and feeding means for feeding said mechanism relative to said guideway including feed operating means movable with said mechanism and cooperating flexible feeding means operatively connected thereto.

41. In a mining machine, a support, a motor having an armature shaft, cutting mechanism on said support including a pivoted cutter bar disposed in a vertical plane, actuating means for said bar including a connection with one end of said armature shaft, a worm gear concentric with the axis of said bar for movement therewith during swinging thereof, a worm meshing with said worm gear, and means including an operative connection with the other end of said armature shaft connected to said worm for swinging said bar in a vertical plane about its pivot.

42. In a mining machine, a support, cutting mechanism reciprocable thereon including a pivoted cutter bar disposed in a vertical plane, a worm gear concentric with the axis thereof and movable therewith during swinging thereof, and power means including a motor having an armature shaft for operation said cutter bar, for feeding said cutting mechanism on said support and for rotating said worm to effect swinging of said bar in a vertical plane about its pivot and including operative connections between one end of said armature shaft and said worm, feeding mechanism actuated by the same end of said armature shaft and mechanism for actuating said bar driven by the opposite end of said armature shaft.

43. In a mining machine, a support, cutting mechanism thereon including a pivoted cutter bar disposed in a vertical plane, a worm gear concentric with the axis thereof and movable therewith during swinging

thereof, a worm meshing with said worm gear, power means, including a motor whose axis of rotation is parallel to the direction of feed of said cutting mechanism and which is bodily movable with said bar, connected between said cutting mechanism and said worm for swinging said bar in a vertical plane about its pivot, and power connections to said cutting mechanism for feeding said bar longitudinally into a face.

44. In a mining apparatus, a wheeled truck, a guide normally disposed longitudinally thereof and having laterally spaced guide members, means for moving said guide longitudinally and angularly relative to said truck, and vertical kerf cutting mechanism movable in said guide including a pivoted cutter bar movable between said guide members.

45. In a mining apparatus, a wheeled truck, a guide normally disposed longitudinally thereof and having laterally spaced guide members, means for disposing said guide transversely relative to said truck in different positions longitudinally of the latter, and vertical kerf cutting mechanism movable in said guide including a pivoted cutter bar movable between said guide members.

46. In a mining apparatus, a wheeled truck, a guide normally disposed longitudinally thereof and having laterally spaced guide members, means for disposing said guide transversely relative to said truck and shifting the position of said guide transversely, and vertical kerf cutting mechanism movable in said guide including a pivoted cutter bar movable between said guide members.

47. In a mining apparatus, a wheeled truck, a member pivoted thereon upon an upright axis and disposable in a horizontal plane, a mining machine receiving guide pivoted on the free end of said member and disposable longitudinally thereof or angularly relative thereto, and a mining machine disposed on and movable longitudinally of said guide and having a cutter bar disposable parallel to said guide to cut beyond the extremity thereof.

48. In a mining apparatus, a wheeled truck, a member pivoted thereon upon an upright axis and disposed in a horizontal plane, a mining machine receiving guide pivoted on the free end of said member and disposable longitudinally of the latter or angularly relative thereto, and a mining machine disposed on and movable longitudinally of said guide and having a pivoted cutter bar disposable parallel to said guide and adapted to cut beyond the end thereof.

49. In a mining apparatus, a wheeled truck, a member pivoted thereon upon an upright axis and disposed in a horizontal plane, an elongated mining machine receiv-

- ing guide pivoted on the free end of said member and disposable longitudinally of the latter or angularly relative thereto, and a mining machine disposed on and movable longitudinally of said guide and having a pivoted cutter bar disposed in a vertical plane to which the major dimension of said guide is parallel.
50. In a mining apparatus, a wheeled truck, a member pivoted thereon upon an upright axis and disposed in a horizontal plane, a mining machine receiving guide having major and minor dimensions pivoted on the free end of said member and disposable longitudinally of the latter or angularly relative thereto, and a mining machine disposed on and movable longitudinally of said guide and having a pivoted cutter bar disposed in a vertical plane intersecting said guide parallel to its major dimension.
51. In a mining machine adapted to cut on the arcwall system, a machine frame including a motor having an axis of rotation parallel to the direction of rectilinear movements of said machine during arcwall cutting, cutting mechanism at one end of said motor including a swinging cutter bar, means for operating said cutting mechanism operatively connectible to one end of said motor, and means for swinging said bar and locking it positively against movement in either direction in adjusted positions operatively connectible to the other end of said motor.
52. In a mining apparatus, a wheeled truck, a support thereon presenting a guideway, kerf cutting mechanism including a pivoted cutter bar movable longitudinally of said guideway with its pivot disposed between the sides of the latter and adapted to cut a vertical kerf, and feeding mechanism for feeding said cutting mechanism oppositely relative to said guideway including feed operating means movable with said cutting mechanism and cooperating flexible feeding means having fixed ends.
53. In a mining machine, a wheeled truck, power operated truck propulsion mechanism, a cutter bar carried by said truck and swingable in a vertical plane, power operated worm gearing for effecting swinging of said bar including a worm rotating on a horizontal axis and a worm wheel secured to said bar, a cutter chain on said bar, and power operated means for effecting circulation of said cutter chain, all of said power operated means being self-contained.
54. In a mining apparatus, a machine frame having a motor intermediate the ends thereof, cutting mechanism at one end of said frame including a pivoted cutter bar having orbitally moving cutting elements, means actuated by one end of said motor for effecting orbital movement of said cutting elements, and means actuated by the other end of said motor for effecting bar swing including a threaded member rotatable on a horizontal axis extending longitudinally of the motor and self-locking power transmitting connections between the same and said bar.
55. In a mining machine, a machine frame including a motor, cutting mechanism at one end of said motor including a swinging cutter bar disposed in a vertical plane, and means for operating said cutting mechanism and reversely swinging said bar respectively connected to opposite ends of said motor, each of said last mentioned means comprising intermeshing gear elements at the end of said motor at which the bar is disposed.
56. In a mining machine, a machine frame including a motor, cutting mechanism at one end of said motor including a swinging cutter bar disposed in a vertical plane, means for operating said cutting mechanism connected to one end of said motor, and self-locking bar swinging mechanism operatively connectible to the opposite end of said motor.
57. In a mining machine, a machine frame including a motor, cutting and feeding mechanisms supported on said frame, operative connections between one end of said motor and said cutting mechanism, operative connections between the other end of said motor and said feeding mechanism, said cutting mechanism being adjustable and disposed in a vertical plane, and means for adjusting said cutting mechanism including gearing at the first end of the motor driven from said operative connections between said feeding mechanism and said motor.
58. In a mining machine adapted to cut on the arcwall system, a machine frame including a motor having an axis of rotation parallel to the direction of rectilinear movements of said machine during arcwall cutting, cutting mechanism including a cutter bar adjustable on an axis on the front end of the frame, means for driving the cutting mechanism from one end of the motor, and a gear train for adjusting the bar about its axis and for locking it in fixed positions operatively connectible to the opposite end of the motor.
59. In a mining machine adapted to cut on the arcwall system, a machine frame including a motor having an axis of rotation parallel to the direction of rectilinear movements of said machine during arcwall cutting, cutting mechanism including a cutter bar adjustable on an axis on the front end of the frame, means for driving the cutting mechanism from one end of the motor, and means for adjusting said bar oppositely about its axis driven from the opposite end.

of said motor including a threaded member and reversing mechanism cooperating therewith.

60. In a mining machine, a machine frame including a motor, cutting mechanism including a cutter bar adjustable on an axis on the front end of the frame, means for driving the cutting mechanism from one end of the motor, and means for adjusting said bar oppositely about its axis driven from the opposite end of said motor including a threaded member rotatable on an axis parallel to the axis of rotation of the motor.

61. In a mining machine, a machine frame including a motor, cutting mechanism including a cutter bar adjustable on an axis on the front end of the frame, means for driving the cutting mechanism from one end of the motor, and means for adjusting said bar oppositely about its axis driven from the opposite end of said motor including a threaded member rotatable on an axis extending longitudinally of the machine frame.

62. In a mining machine, a machine frame including a motor, cutting mechanism including a cutter bar adjustable on a substantially horizontal transverse axis on the front end of the frame, said motor having an axis of rotation parallel to the plane of bar swing, means for driving the cutting mechanism from one end of the motor, and means for adjusting the bar about its axis and for locking it in fixed positions operatively connectible to the opposite end of the motor.

63. In a mining machine, a machine frame including a motor, cutting mechanism including a cutter bar adjustable on a substantially horizontal transverse axis on the front end of the frame, means for driving the cutting mechanism from one end of the motor, and means for adjusting said bar oppositely about its axis driven from the opposite end of said motor including a threaded member and reversing mechanism cooperating therewith.

64. In a mining machine, a machine frame including a motor, cutting mechanism including a cutter bar adjustable on a substantially horizontal transverse axis on the front end of the frame, means for driving the cutting mechanism from one end of the motor, and means for adjusting said bar oppositely about its axis driven from the opposite end of said motor including a threaded member rotatable on an axis parallel to the axis of rotation of the motor.

65. In a mining machine, a machine frame including a motor, cutting mechanism including a cutter bar adjustable on a substantially horizontal transverse axis on the front end of the frame, means for driving the cutting mechanism from one end of the motor, and means for adjusting said bar oppositely about its axis driven from the opposite end of said motor including a threaded member

rotatable on a longitudinally extending axis.

66. In a mining apparatus, a machine frame, comprising a motor disposed intermediate the ends thereof, cutting mechanism including a pivoted cutter bar adjacent one end of said frame and actuated by the adjacent end of said motor, a member rotatable on an axis extending longitudinally of said frame and having a threaded portion, bar swinging means including an element cooperatively engaging said threaded portion, and means for rotating said threaded member actuated by the other end of said motor including a pair of bevel gears coaxial with said member, a driving pinion driven by said motor and meshing with said bevel gears, and means for selectively connecting said bevel gears in driving relation to said member.

67. In a mining apparatus, a machine frame comprising a motor intermediate its ends, cutting mechanism arranged at one end of said frame and comprising a pivoted cutter chain carrying cutter bar, operative connections between the adjacent end of said motor and said cutter chain, a bevel pinion at the opposite end of said motor, power transmission connections between said bevel pinion and said opposite end of said motor, bar swinging means driven by said bevel pinion, and machine feeding mechanism driven from said power transmission connections at a point in the latter between the motor and the bevel pinion.

68. In a mining apparatus, a machine frame comprising a motor intermediate its ends, cutting mechanism arranged at one end of said frame and comprising a pivoted cutter chain carrying cutter bar, operative connections between the adjacent end of said motor and said cutter chain, a bevel pinion at the opposite end of said motor, power transmission connections between said bevel pinion and said opposite end of said motor, bar swinging means driven by said bevel pinion, and reversible machine feeding mechanism driven from said power transmission connections at a point in the latter between the motor and the bevel pinion.

69. In a mining apparatus, a machine frame comprising a motor intermediate its ends, cutting mechanism arranged at one end of said frame and comprising a pivoted cutter chain carrying cutter bar, operative connections between the adjacent end of said motor and said cutter chain, a bevel pinion at the opposite end of said motor, power transmission connections between said bevel pinion and said opposite end of said motor, bar swinging means driven by said bevel pinion, and plural speed reversible machine feeding mechanism driven from said power transmission connections at a point in the latter between the motor and the bevel pinion.

70. In a mining apparatus, a machine frame comprising a motor intermediate its ends, cutting mechanism arranged at one end of said frame and comprising a pivoted cutter chain carrying cutter bar, operative connections between the adjacent end of said motor and said cutter chain, a bevel pinion at the opposite end of said motor, power transmission connections between said bevel pinion and said opposite end of said motor, bar swinging means driven by said bevel pinion, and machine feeding mechanism driven from said power transmission connections at a point in the latter between the motor and the bevel pinion and operative to feed said machine in different directions at different speeds.
71. In a mining machine adapted to arc-wall cutting, a vertically swingable shearing cutter chain carrying cutter bar, a motor provided with a plurality of power transmitting elements rotatable on axes parallel to the path of machine movement during cutting, operative connections between one of said elements and said cutter chain, and a gear train directly connecting another of said elements to said bar to effect bar swing and including clutch controlled reversing mechanism.
72. In a mining machine adapted to arc-wall cutting, a vertically swingable shearing cutter chain carrying cutter bar, a cutter chain driving sprocket coaxial with the pivot of said bar, a bar swinging member movable about said bar pivot, a motor having a plurality of power transmitting elements rotatable on axes parallel to the path of machine movement during cutting, and operative connections between one of said elements and said sprocket and between the other and said member, said last mentioned connections including a screw member at the end of the motor adjacent the bar.
73. In a mining machine, a machine frame carrying a pivoted cutter bar, a motor on said machine frame having a power shaft rotating on an axis parallel to the plane of bar swing and extending longitudinally of said machine frame, said cutter bar provided with a cutter chain, means affording operative connection between said motor power shaft and said cutter chain to drive the latter, means including a reversing mechanism independent of said last named means affording operative connection between said motor and said cutter arm to swing the latter about its pivotal axis positively in either direction merely on opposite actuations of said reversing mechanism, and flexible feeding means for feeding said machine directly on a mine bottom.
74. In a mining machine, a machine frame, a motor thereon having a power shaft extending longitudinally of said frame, a cutter chain carrying bar swingable about a substantially horizontal transverse axis at one end of said motor, motor operated cutter chain driving means, and means driven by the end of said power shaft remote from said cutter bar for adjusting the latter oppositely about its axis, said means comprising connections including reversing gearing and operative automatically on operation of said reversing mechanism to effect positive swing in either direction.
75. In a mining machine, a machine frame, a motor thereon having a power shaft extending longitudinally of said frame, a cutter chain carrying bar swingable about a horizontal axis at one end of said motor, motor operated cutter chain driving means, and means driven by the end of said power shaft remote from said cutter bar and including a threaded member rotatable on a longitudinally extending axis for adjusting the bar oppositely about its axis.
76. In a mining machine, a machine frame, a motor thereon having a power shaft extending longitudinally of said frame, a cutter chain carrying bar swingable about a horizontal axis at one end of said motor, motor operated cutter chain driving means, and means driven by the end of said power shaft remote from said cutter bar and including an externally threaded member rotatable on a longitudinal axis for adjusting the latter oppositely about its axis.
77. In a mining machine, a machine frame, a motor thereon having a power shaft extending longitudinally of said frame, a cutter chain carrying cutter bar pivotable about a horizontal axis at one end of said motor, a cutter chain driving sprocket rotatable on said axis, driving gearing therefor including a bevel gear coaxial with said sprocket and a motor driven bevel pinion rotatable on a longitudinally extending axis, and means for swinging said bar including a threaded member rotating on a horizontal axis lying in a longitudinally extending vertical plane and having driving connections permitting reverse rotation thereof without reversal of the motor.
78. In a mining machine, a machine frame including a motor, cutting mechanism including a cutter bar adjustable on an axis on the front end of said frame, means for driving said cutting mechanism from one end of said motor, and means for adjusting the bar about its axis driven from the opposite end of said motor and including reverse bevels rotating on an axis parallel to the axis of rotation of said motor.
79. In a mining machine, a machine frame including a motor, cutting mechanism including a cutter bar adjustable on a transverse axis on the front end of said frame, means for driving said cutting mechanism from one end of said motor, and means for adjusting the bar about its axis driven from

the opposite end of said motor and including reverse bevels rotating on an axis parallel to the axis of rotation of said motor.

80. In a mining machine, a machine frame including a motor, cutting mechanism including a cutter bar adjustable on an axis on the front end of said frame, means for driving said cutting mechanism from one end of said motor, and means for adjusting the bar about its axis driven from the opposite end of said motor and including reverse bevels rotating on an axis parallel to the axis of rotation of said motor and at the last mentioned end of the latter.

81. In a mining machine, a machine frame including a motor, cutting mechanism including a cutter bar adjustable on a transverse axis on the front end of said frame, means for driving said cutting mechanism from one end of said motor, and means for adjusting the bar about its axis driven from the opposite end of said motor and including reverse bevels rotating on an axis parallel to the axis of rotation of said motor and at the last mentioned end of the latter.

82. In a mining machine, a machine frame including a motor, cutting mechanism including a cutter bar carrying orbitally moving cutting elements and adjustable on an axis on the front end of said frame, means for driving said cutting mechanism from one end of said motor, and means for adjusting said bar about its axis and effecting opposite rectilinear feeds thereof while said elements traverse at all times their orbits in the same direction, said last mentioned means driven from the opposite end of said motor and including, to effect bar adjustment about its axis, a plurality of gear members on the front end of the machine.

83. In a mining machine, a machine frame including a motor, cutting mechanism including a cutter bar carrying orbitally moving cutting elements and adjustable on a substantially horizontal transverse axis on the front end of said frame, means for driving said cutting mechanism from one end of said motor, and means for adjusting said bar about its axis and effecting opposite rectilinear feeds thereof while said elements traverse at all times their orbits in the same direction, said last mentioned means driven from the opposite end of said motor and including worm gearing at the front end of the machine for effecting bar swing.

84. In a mining machine, a machine frame including a motor, cutting mechanism including a cutter bar carrying orbitally moving cutting elements and adjustable on an axis on the front end of said frame, means for driving said cutting mechanism from one end of said motor, and means for adjusting said bar about its axis automatically operative on cessation of adjustment to lock it against movement in either direction and

means for effecting opposite rectilinear feeds of said cutting mechanism while said elements traverse at all times their orbits in the same direction, said last two mentioned means driven from the opposite end of said motor and including a flexible element and rotatable means cooperating therewith.

85. In a mining machine, a machine frame including a motor, cutting mechanism including a cutter bar carrying orbitally moving cutting elements and adjustable on a transverse axis on the front end of said frame, means for driving said cutting mechanism from one end of said motor, means for adjusting said bar about its axis automatically operative on cessation of adjustment to lock it against movement in either direction, and effecting opposite rectilinear feeds thereof while said elements traverse at all times their orbits in the same direction, said last mentioned means driven from the opposite end of said motor and including a flexible element and rotatable means cooperating therewith.

86. In a mining machine, a machine frame including a motor, cutting mechanism including a cutter bar carrying orbitally moving cutting elements and adjustable on an axis on the front end of said frame, means for driving said cutting mechanism from one end of said motor and means for adjusting said bar about its axis and effecting opposite rectilinear feeds thereof while said elements traverse at all times their orbits in the same direction, said last mentioned means driven from the opposite end of said motor and including a flexible element and rotatable means cooperating therewith, and a member rotatable in either direction on an axis horizontal and parallel to the direction of rectilinear feed and disposed at the front end of the frame.

87. In a mining machine, a machine frame including a motor, cutting mechanism including a cutter bar carrying orbitally moving cutting elements and adjustable on a transverse axis on the front end of said frame, means for driving said cutting mechanism from one end of said motor and means for adjusting said bar about its axis and effecting opposite rectilinear feeds thereof while said elements traverse at all times their orbits in the same direction, said last mentioned means driven from the opposite end of said motor and including a flexible element and rotatable means cooperating therewith, and a member rotatable in either direction on an axis horizontal and parallel to the direction of rectilinear feed and disposed at the front end of the frame.

88. In a mining machine, a machine frame including a motor, cutting mechanism including a cutter bar carrying orbitally moving cutting elements and adjustable on an axis on the front end of said frame, means

for driving said cutting mechanism from one end of said motor, means for adjusting said bar about its axis, and means effecting opposite rectilinear feeds thereof while said elements traverse at all times their orbits in the same direction, each of said last two mentioned means driven from the opposite end of said motor and one including a flexible element and rotatable means cooperating therewith and the other a member individual thereto and rotatable in either direction on an axis horizontal and parallel to the direction of rectilinear feed.

89. In a mining machine, a machine frame including a motor, cutting mechanism including a cutter bar carrying orbitally moving cutting elements and adjustable on a substantially horizontal transverse axis on the front end of said frame, means for driving said cutting mechanism from one end of said motor, means for adjusting said bar about its axis, and means effecting opposite rectilinear feeds thereof while said elements traverse at all times their orbits in the same direction, each of said last two mentioned means driven from the opposite end of said motor and one including a flexible element and rotatable means cooperating therewith and the other a member individual thereto and rotatable in either direction on an axis horizontal and parallel to the direction of rectilinear feed.

90. In a mining machine, a machine frame including a motor, cutting mechanism at one end of said motor including a swinging cutter bar pivotable about a horizontal axis transverse to said frame, means for operating said cutting mechanism operatively connectible to one end of said motor, and means for swinging said bar and locking it in adjusted positions operatively connectible to the other end of said motor and including a worm and a worm wheel, the latter rigid with the bar.

45 91. In a mining machine, a machine frame including a motor, cutting mechanism at one end of said motor including a swinging cutter bar pivotable about a horizontal axis transverse to said frame, means for operating said cutting mechanism operatively connectible to one end of said motor and means for swinging said bar and locking it in adjusted positions operatively connectible to the other end of said motor, said bar swinging mechanism including reverse bevels rotating on an axis parallel to the plane of bar swing.

92. In a mining machine, a machine frame including a motor, cutting mechanism at one end of said motor including a swinging cutter bar pivotable about a horizontal axis transverse to said frame, means for operating said cutting mechanism operatively connectible to one end of said motor, and means for swinging said bar and locking it in ad-

justed positions operatively connectible to the other end of said motor, said bar swinging mechanism including reverse bevels rotating on a horizontal axis parallel to the plane of bar swing.

70 93. In a mining machine, a pivoted cutter bit carrying cutter bar swingable in a vertical plane, actuating means for said bits, and means for swinging said bar in opposite directions including reverse bevels rotating simultaneously in opposite directions on an axis parallel to the plane of bar swing.

75 94. In a mining machine, a pivoted cutter bit carrying cutter bar swingable in a vertical plane, actuating means for said bits, and means for swinging said bar in opposite directions including reverse bevels rotating on a fixed horizontal axis parallel to the plane of bar swing.

80 95. In a mining machine, a pivoted cutter bit carrying cutter bar swingable in a vertical plane, actuating means for said bits, and means for swinging said bar in opposite directions including reverse bevels rotating on an axis parallel to the plane of bar swing and adjacent the end of the machine remote from said bar.

85 96. In a mining machine, a pivoted cutter bit carrying cutter bar swingable in a vertical plane, actuating means for said bits, and means for swinging said bar in opposite directions including reverse bevels rotating on a horizontal axis parallel to the plane of bar swing and adjacent the end of the machine remote from said bar.

90 97. In a mining machine, a wheeled truck, power operated truck propulsion mechanism, a cutter bar carried by said truck and swingable in a vertical plane, power operated worm gearing for effecting swinging of said bar including a worm rotatable on a horizontal axis parallel to the plane of bar swing and a worm wheel whose axis is alined with the axis of bar swing, a cutter chain on said bar, and power operated means for effecting circulation of said cutter chain, all of said power operated means being self-contained.

95 98. In a mining machine, a wheeled truck, power operated truck propulsion mechanism, a cutter bar carried by said truck and swingable in a vertical plane, power operated worm gearing for effecting swinging of said bar including a worm rotatable on a horizontal axis parallel to the plane of bar swing and driving gearing therefor including reverse bevels, a cutter chain on said bar, and power operated means for effecting circulation of said cutter chain, all of said power operated means being self-contained.

100 99. In a mining machine, a wheeled truck, power operated truck propulsion mechanism, a cutter bar carried by said truck and swingable in a vertical plane, power operated worm gearing for effecting swinging of said bar including a worm rotatable on a horizon-

- tal axis parallel to the plane of bar swing and driving gearing therefor including reverse bevels coaxial therewith, a cutter chain on said bar, and power operated means for effecting circulation of said cutter chain, all of said power operated means being self-contained.
100. In a mining apparatus, a machine frame having a motor intermediate the ends thereof, cutting mechanism at one end of said frame including a horizontally pivoted cutter bar having orbitally moving cutting elements, means actuated by one end of said motor for effecting orbital movement of said cutting elements, and means actuated by the other end of said motor for effecting bar swing including a threaded member rotatable on a horizontal axis and self-locking power transmitting connections between the same and said bar.
101. In a mining apparatus, a machine frame having a motor intermediate the ends thereof, cutting mechanism at one end of said frame including a horizontally pivoted cutter bar having orbitally moving cutting elements, means actuated by one end of said motor for effecting orbital movement of said cutting elements, and means actuated by the other end of said motor for effecting bar swing including a threaded member rotatable on a horizontal axis extending longitudinally of the motor and self-locking power transmitting connections between the same and said bar.
102. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis.
103. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis.
104. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis.
105. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis.

In testimony whereof I affix my signature.
FRANK CARTLIDGE.

tal axis parallel to the plane of bar swing and driving gearing therefor including reverse bevels coaxial therewith, a cutter chain on said bar, and power operated means for effecting circulation of said cutter chain, all of said power operated means being self-contained.

100. In a mining apparatus, a machine frame having a motor intermediate the ends thereof, cutting mechanism at one end of said frame including a horizontally pivoted cutter bar having orbitally moving cutting elements, means actuated by one end of said motor for effecting orbital movement of said cutting elements, and means actuated by the other end of said motor for effecting bar swing including a threaded member rotatable on a horizontal axis and self-locking power transmitting connections between the same and said bar.

101. In a mining apparatus, a machine frame having a motor intermediate the ends thereof, cutting mechanism at one end of said frame including a horizontally pivoted cutter bar having orbitally moving cutting elements, means actuated by one end of said motor for effecting orbital movement of said cutting elements, and means actuated by the other end of said motor for effecting bar swing including a threaded member rotatable on a horizontal axis extending longitudinally of the motor and self-locking power transmitting connections between the same and said bar.

102. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis and reverse bevels rotatable on a horizontal axis.

posite end of said motor and including a flexible chain member for effecting the rectilinear bodily movements and gearing wholly independent of said chain member for effecting bar swing.

103. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis.

104. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis and reverse bevels rotatable on a horizontal axis.

105. In a mining machine, a motor having a rotating shaft, a frame supporting said motor, a vertically swinging cutting mechanism at one end of and actuated by such end of said motor, and means for effecting opposite rectilinear bodily movements of said cutting mechanism and opposite swinging movements of said bar actuated by the opposite end of said motor and including a chain engaging sprocket rotatable on a vertical axis and reverse bevels rotatable on a horizontal axis in a plane above said sprocket.

In testimony whereof I affix my signature.
FRANK CARTLIDGE.

CERTIFICATE OF CORRECTION.

Patent No. 1,648,876.

Granted November 8, 1927, to

FRANK CARTLIDGE.

It is hereby certified that error appears in the printed specification of the above numbered patent requiring correction as follows: Page 1, line 24, for the misspelled word "foreging" read "foregoing"; same page, line 89, before the word "bar" insert the word "cutter"; page 4, line 17, claim 5, and page 5, line 40, claim 20, after the word "latter" insert a comma; page 5, line 127, claim 28, after the word "latter" insert the words "and disposed longitudinally thereof"; page 6, line 40, claim 32, after the word "plane" and in line 106, claim 36, after the word "motor" strike out the "comma"; and that the said Letters Patent should be read with these corrections therein that the same may conform to the record of the case in the Patent Office.

Signed and sealed this 17th day of January, A. D. 1928.

Seal.
